UNITED STATES PATENT OFFICE.

AARON T. FOSTER AND MARTIN L. JONES, OF CHILlicothe, OHIO.

CONCRETE-MOLD.

No. 820,188.

Specification of Letters Patent.

Patented May 8, 1906.

Application filed April 1, 1905. Serial No. 253,223.

To all whom it may concern:

Be it known that we, AARON T. FOSTER and MARTIN L. JONES, citizens of the United States, residing at Chillicothe, in the county of Ross and State of Ohio, have invented certain new and useful Improvements in Concrete-Molds, of which the following is a specification.

Our invention relates to a new and useful improvement in concrete-molds, and more particularly to molds for producing monolithic walls.

The object of the invention is to provide a mold of the sectional or knockdown type in which the side boards are held rigidly in position between interlocking clamps, the latter being adapted to readily fit together and to be easily and expeditiously disengaged from each other.

Another feature resides in the means for holding the clamps in contact with the side boards and the latter in proper relation to each other and also means for placing the parts of the mold under tension.

Finally, the object of the invention is to provide a device of the character described that will be strong, durable, efficient, simple, and comparatively inexpensive to make and one in which the several parts will not be liable to get out of working order.

With the above and other objects in view the invention consists of the novel details of construction and operation, a preferable embodiment of which is described in the specification and illustrated in the accompanying drawings, wherein—

Figure 1 is a side elevation of a section of our mold, showing the clamps in position. Fig. 2 is a plan view of the same. Fig. 3 is a partial elevation of the opposite side from that shown in Fig. 1. Fig. 4 is a transverse vertical sectional view taken on the line $x-x$ of Fig. 1, and Fig. 5 is a vertical section taken through one of the clamps and its tension means and showing a portion of one of the wires in engagement therewith.

In the drawings the numeral 1 designates the side boards, which, it is understood, are to be of such length as the occasion may require, and in constructing walls of considerable length it is understood that these side boards are arranged in sections, having their ends abutting. However, for the purposes of illustration we have deemed it sufficient to only show one of these sections and the parts associated therewith. In forming an ordi-

nary wall it will generally be found that six side boards, three on each side, will be sufficient, although it is understood that a greater number of boards may be employed, if desired. The boards are arranged as stated, three on each side and one above the other in courses or tiers, as shown in Figs. 1, 3, and 4. In setting up the mold the width of the wall is first determined and then short blocks 2, having a width equal to the predetermined width of the wall, are provided. These blocks are placed at the ends and in the center at the top and bottom of each board, so as to break joint with the meeting edges of the boards and to extend between the upper sides of the upper boards and the lower sides of the lower boards, as clearly shown in Fig. 4. In this manner the space produced between the side boards on each side of the mold will have the width of the finished wall. To hold the boards in position, we provide clamp members 3 and 4, adapted to stand opposite each other. Each clamp member is provided at one end with separated lugs 5, projecting beyond its end and adapted to receive a central lug 6, formed on the adjacent end of the next adjacent clamp member; it being understood that each clamp member is thus formed at one end with a single lug 6 and at its opposite end with separated lugs 5, provided at each side. The lugs are offset, as indicated in Figs 4 and 5, so that when they are brought into interlocking engagement their projecting portions will engage over the outer surfaces of the clamps and allow the inner surfaces of the same to lie flush and in direct contact with the side boards 1. These clamps are so arranged as to cause their interlocking ends to mutually engage in the center of the side boards or between the upper and lower edge of each board, thereby bringing the central or solid portion of each clamp opposite the meeting edges of two adjacent boards, and thereby break joining with the same.

The clamps 4 on one side are formed central with grooved bosses 7 and also with central openings 8, extending through the clamps and communicating with the grooved portions of the bosses. Wires 9 are passed between the meeting edges of the boards through the openings 8 and fastened about the said bosses 7. The clamps 3 on the other side of the mold are constructed to receive the said wires 9, which extend across the mold and in this way hold the boards together. The clamping members on the opposite side

are formed with integral central collar portions 10, each provided with an angular bore 11, in which a hollow screw 12 is loosely fitted. The screw is formed on its inner end 5 with an angular head 13, adapted to fit slidably in the bore 11, but holding the screw 12 against rotation. The hollow screw 12 extends some distance outwardly or beyond the collar 10 and is provided with a wing-nut 14, 10 which bears against the outer end of the collar. At its extreme outer end the hollow screw 12 carries a grooved boss 15, similar to the boss 7, but slightly longer. One of the wires 9 is passed through the hollow screw 15 into the grooved boss 15 and securely caught 15 about the same, the wire being drawn as tight as possible. In this way the mold is assembled and after the wires have been fastened and stretched between each pair of adjacent lugs the wing-nuts 14 are turned so 20 as to draw the hollow bolts 12 outward or away from the side boards, which places the wires 9 under tension and draws the side boards 1 and clamps 3 and 4 together, causing the said side boards to firmly impinge the space-blocks 2, and thus producing a strong and rigid mold. It will be apparent that considerable tension can be placed on the wires 9 by turning the wing-nuts 14 and that 25 the boards will be held in position during the tamping of the concrete, which is thrown in between the side boards.

As the concrete is tamped in and its level gradually raised the space-blocks 2 are 30 knocked out or removed, so that a practically solid or monolithic wall may be produced. As the wall is built up toward the top of the third board the bottom clamps on each side may be removed by first loosening the wing-nuts 14 to relieve the tension of the wires 9 and the ends of the wires then unfastened from the bosses 7 and 15 and the clamps removed. The lowermost side board on each side is then removed and placed on top of the 40 uppermost boards and the clamps engaged with the uppermost clamps and the mold built up, as described. It will be apparent that the uppermost clamps will always project half their length above the uppermost board, thus facilitating the placing of additional boards as the mold is built up. When the side boards are removed from the wall, the wires 9 may be clipped off and withdrawn 45 from the wall or they may be allowed to remain in the wall and clipped off close to its sides.

The clamp members are provided on their inner sides with longitudinal grooves 16, extending from opposite sides of the opening 11 50 and having sufficient depth to receive the wire 9, so that when the tension is relieved and it is desired to disengage one of the clamps from the other the said clamp may be moved either up or down, the wire being received in 55 the groove, and thus allowing the lugs to be

readily drawn out of engagement with each other. It is obvious that if these grooves 16 were not provided the wire bending in between the inner surface of the clamp and the side boards would cause the clamp to swing outward at its free end, and thus cause the interlocking lugs at the opposite end to bind and prevent the ready disengagement from the adjacent clamp members. 70

By employing wires instead of rods or the like we are enabled to produce a more satisfactory mold at less expense for the reason that the wire per foot is cheaper than the rods and neither nuts nor headed ends are required. Further, it is practically impossible to clip off rods and leave them in the wall, and where they are removed the opening left must be filled from end to end, else the wall will be porous and damp. Where a wire is used, it is generally preferable to clip off the ends of the wire close up to the wall and allow it to remain therein, as it serves to tie the particles of concrete together and strengthen the wall. However, if it is removed such a small opening is left through the wall that by plugging it at each end satisfactory results are had. Another novel feature of our invention resides in the interlocking of the clamp members, as it will be obvious that when two or more of the members are interlocked at their ends they will be as rigidly connected as if made in a single piece and when caused to lie flat on the side boards cannot possibly have any lateral movement independent of each other. 95

Having now fully described our invention, what we claim, and desire to secure by Letters Patent, is—

1. In a device of the character described, the combination with a plurality of superimposed side boards of a plurality of clamping members located upon the exterior faces of said side boards and adapted to interlock with each other, a plurality of flexible connecting members engaging the clamping members upon one side of the mold, said flexible members passing between the adjacent edges of the said side boards and being engaged by members upon the opposite side of said mold adapted to place said connecting members under tension, said flexible connecting members being adapted to remain in the said monolithic structure and to form a part thereof. 105

2. A clamping device for monolithic molds comprising opposed clamp members each having two projections at one end and a single projection at the other end, said projections adapted to interlock when the clamp members are assembled, and means for drawing the clamp members into clamping relation. 110

3. In a device of the character described, the combination with a plurality of superimposed side boards, of a plurality of clamp- 115

ing members located upon the exterior of said side boards and adapted to interlock with each other, a plurality of connecting members engaging the clamping members upon one side of the mold, said connecting members passing between the adjacent edges of the side boards and being engaged by devices upon the opposite side of said mold adapted to place said connecting members under tension, said connecting members be-

ing adapted to remain in the said monolithic structure and to form a part thereof.

In testimony whereof we affix our signatures in presence of two witnesses.
